Attorney.

UNITED STATES PATENT OFFICE

1,981,156

TELEPHONE CALL REMINDER

William F. Timmermann, Hempstead, N. Y.

Application November 20, 1933, Serial No. 698,804

2 Claims. (Cl. 40—10.5)

The invention relates to devices for listing incoming telephone calls. It has for its main object to provide a device which contains means for holding a notation slip and which may be placed on the "hand set" of the so-called "French type" telephone, so that this hand set cannot be removed without first removing the device. Another object is to so construct the device that it may serve other utilitarian or ornamental purposes. A further object is to provide a device of simple construction and attractive appearance which can be manufactured at low cost.

These and various other objects and advantages will be readily understood from the following description and from the accompanying drawing of preferred embodiment of the invention in which, however, modifications may be made without departing from the scope of the appended claims. In the drawing

20 Fig. 1 is a fragmental front view of a telephone on which my device has been placed,
Fig. 2 a side view of the device itself,
Fig. 3 a front view of a somewhat modified device, and

25 Fig. 4 a top view of Fig. 3.
Referring first to Figs. 1 and 2, a part of the stand of a so-called "French" telephone is shown at 10 and the hand set at 11. My device consists of a base 12 in which a channel-shaped groove 13 is formed and on top of which a paper clip, or holder, 14 is secured. The groove and the bottom of the base is preferably covered with a piece of felt, or other soft fabric, 15.

The device is used in this manner. Ordinarily, 35 it rests on a desk or table on which the telephone is also located. When a telephone call is received and the person for whom the call is intended is absent, a notation is made on a slip of paper 16 and this slip is secured in the spring 40 clip 14. The whole device is now placed on the hand set 11, as shown in Fig. 1. It is evident

that the telephone cannot now be used again without the removal of the device and that the removal of the device will call attention to the notation on the paper slip, thus eliminating any danger of the call being forgotten.

When not in use the device will serve as a paper weight, but it may be made to serve many other useful or ornamental purposes. An example of this is illustrated in Figs. 3 and 4 where a holder 17 for a box of matches or for a package of cigarettes is shown secured on top of the base. In this case a paper clip 18 is formed on the holder. It will be readily seen that the device may thus be constructed to serve many other useful purposes.

Having described my invention and its objects, what I claim as new and wish to protect by Letters Patent is:

1. In combination with a French-type telephone, a relatively heavy base having a length 75 slightly shorter than the distance between the pairs of prongs provided on the stands which are used for supporting the hand-set of such telephones, a deep groove formed in the bottom of the base for loosely straddling the hand-set 80 between the said prongs when the hand-set is in place on the stand, and a memorandum holder mounted on the base.

2. In combination with a French-type telephone, a relatively heavy base having a length 85 slightly shorter than the distance between the pair of prongs provided on the stands which are used for supporting the hand-set of such telephones, a deep groove formed in the bottom of the base for loosely straddling the hand-set between the said prongs when the hand-set is in 90 place on the stand, a memorandum holder mounted on the base, and the bottom of the base made flat to form a foot upon which the device will rest when not in use on the hand-set. 95

WILLIAM F. TIMMERMANN.
